UNITED STATES PATENT OFFICE.

HARRY D. APPLEBY, OF NEW YORK, N. Y., ASSIGNOR OF ONE-HALF TO RICHARD B. COOPER, OF NEW YORK, N. Y.

BLOCK OR TILE FOR WALL CONSTRUCTION.

1,365,444.

Specification of Letters Patent. Patented Jan. 11, 1921.

Application filed July 31, 1918. Serial No. 247,566.

To all whom it may concern:

Be it known that I, HARRY D. APPLEBY, a citizen of the United States, residing at city of New York, borough of Manhattan, 5 and State of New York, have invented certain new and useful Improvements in Blocks or Tiles for Wall Construction, of which the following is a specification.

My invention relates to channeled building blocks or tiles employed in the construction of walls, and has for its object to provide an improved construction of block or tile embodying a positive grip for handling and laying the same, and also to provide 15 for resisting lateral displacement of the blocks or tiles when placed in position in a wall.

These objects I accomplish in the manner and by the means hereinafter more definitely 20 set forth and claimed, reference being had to the accompanying drawing in which:—

Figure 1 is a perspective view of a building block or tile, embodying my invention.

Fig. 2 is a similar view taken through a 25 portion of a wall, illustrating the manner in which the blocks or tiles are assembled or laid.

Similar numerals of reference denote corresponding parts in the two views.

In the said drawing, the reference numerals 1 and 2 denote longitudinal load-sustaining members, the side load-sustaining members 1 being longitudinally apertured at 3, forming chambers preferably rectangular in cross area, and extending from end to end of the block or tile. The central load-sustaining member 2 has its sides 4 inclined or undercut, for the purpose of providing a 35 positive grip in handling the block or tile.

The load-sustaining members 1 and 2 are 40 separated by grooves or channels 5 extending from end to end of the block or tile, and the upper or mortar-receiving surfaces of the members 1 are in the same plane and 45 constitute the upper face of said block or tile. The top surface of the central load-sustaining member 2 lies below the plane of the top surface of the load-sustaining members 1, which provides the space necessary 50 to receive a layer of mortar or cement between the blocks or tiles at this point. The lower portions of the load-sustaining members 1 and 2 are connected by a transverse web 6, of substantially uniform thickness, 55 lying below a plane passing horizontally

through the center of the block or tile, said web 6 projecting below the plane of the bottom surfaces of the side load-sustaining members 1. It will be observed that the top face of the central member 2 does not project above the top surfaces of the side members 1, thus avoiding any protuberance above the upper face of said block or tile. Furthermore, by forming the central longitudinal member 2 with undercut sides 4, I insure a 60 positive grip. The size and weight of these blocks necessitates that the workman shall be able to grip firmly the block or tile with his fingers in lifting and manipulating the same, as otherwise the lifting and setting 65 of these blocks or tiles in the course of the usual day's work, during which time several hundred blocks or tiles must be handled, would impose too great a strain upon the hand of the workman. 70

By providing that the horizontal web 6 shall project below the bottom surfaces of the side load-sustaining members 1, and that the top surface of the central load-sustaining member 2 shall be depressed below the top 75 surfaces of the side load-sustaining members 1, the lateral displacement of the blocks or tiles with respect to each other more effectively is resisted, because this formation will act as a lock. This projection 6 will not be 80 objectionable in stacking the blocks or tiles for transportation or storage, because the depression of member 2, is substantially equal to the projection of the web 6, and the bottom surface of the latter is broad enough 85 to give sufficient bearing when these blocks or tiles are piled in alternate layers at right angles to each other. 90

Having thus described my invention, what I claim as new and desire to secure by 95 Letters Patent, is:—

A block or tile for wall construction, comprising a plurality of longitudinal spaced apart load-sustaining members, the upper and lower surfaces of the side load-sustaining members, respectively, lying in common planes, the upper surface of the central load-sustaining member being depressed below the plane of the upper surfaces of the side load-sustaining members, and a horizontal transverse web connecting the load-sustaining members arranged substantially below a plane passing horizontally through the center of the block or tile, said transverse web projecting below the plane of the 100 side load-sustaining members, and a horizontal transverse web connecting the load-sustaining members arranged substantially below a plane passing horizontally through the center of the block or tile, said transverse web projecting below the plane of the 105 side load-sustaining members, and a horizontal transverse web connecting the load-sustaining members arranged substantially below a plane passing horizontally through the center of the block or tile, said transverse web projecting below the plane of the 110 side load-sustaining members.

lower surfaces of the side load-sustaining members and forming with the lower portions of the load-sustaining members a base for the block, said central load-sustaining member being disposed between and spaced from said side load-sustaining members and adapted for the purposes of a hand hold, all

parts of the block being included between the plane of the upper surfaces of said side load-sustaining members and the bottom surface 10 of said transverse web.

In testimony whereof, I have hereunto set my hand.

HARRY D. APPLEBY.
